UNITED STATES PATENT OFFICE.

EDWIN DONALDSON, OF BROOKLYN, NEW YORK, ASSIGNOR TO INTERNATIONAL BLIND STITCH COMPANY, OF NEW YORK, N. Y., A CORPORATION OF NEW YORK.

SEWING-MACHINE ATTACHMENT FOR OVEREDGE OR BLIND STITCHING.

SPECIFICATION forming part of Letters Patent No. 709,308, dated September 16, 1902.

Application filed December 26, 1901. Serial No. 87,335. (No model.)

To all whom it may concern:

Be it known that I, EDWIN DONALDSON, a citizen of the United States, and a resident of the city of New York, borough of Brooklyn, in the State of New York, have invented certain new and useful Improvements in Sewing-Machine Attachments for Overedge or Blind Stitching and Coöperating Parts of Sewing-Machines, of which the following is a specification, reference being had to the accompanying drawings, in which—

Figure 1 is a top view of my improved attachment, showing its combination with the work or sewing plate and base and also with the feeder of the machine. Fig. 2 is a side view of Fig. 1, showing the bed of the machine in section. Fig. 3 is a detail elevation of the pusher-bar and its actuating-cam. Fig. 4 is a detail, partly in section, showing my eccentric adjusting and fastening pin in perspective. Fig. 5 is a transverse or side view of Fig. 4 to illustrate the same parts. Fig. 6 is a top view of a portion of the attachment, including my adjusting device, and of clamping-screw B⁷ in section. Fig. 7 is a top view of the work or sewing plate and of a portion of the base of the machine. Fig. 8 is an elevation, on an enlarged scale, of my eccentric adjusting and securing pin. Fig. 9 is a top view of Fig. 8. Fig. 10 is a perspective view, on a greatly-enlarged scale, of my improved feeder. Fig. 11 is an elevation, on a greatly-enlarged scale, of my improved presser-foot. Fig. 12 is a top view of Fig. 11.

My present inventions relate to improvements in sewing-machine attachments for overedge or blind stitching, such as are described, for instance, in United States Letters Patent No. 678,908, granted to me and to Thomas H. Ross, assignors to the Ross Attachment & Machine Company, on July 23, 1901, and in which the overedge or blind stitching is accomplished by pushing the edge of the fabric away from under the needle at each alternate descent of the latter, the said movement of the fabric being thus accomplished intermittently by means of a pusher-bar which engages with and moves the said edge intermittently and to which

pusher-bar the requisite motion is communicated from the needle-bar by a train of intermediate mechanism. For instance, as shown in Figs. 1 and 2 of the drawings, a vertical slide-bar F² is reciprocated within suitable guideways contained in a vertical standard F, being a part of the attachment. The said slide-bar is caused to move upwardly vertically by the engagement of its downward extension F⁴ with the set-screw A⁴, which secures the needle A³ to the needle-bar A', and downwardly by the action of a spring F⁵. A pawl F⁶ is pivoted to the said slide-bar and engages at each upward movement of the latter with one of the six equidistant spokes of a trundle-wheel E', on the end of which is mounted a three-sided cam E, which turns with the trundle-wheel and in such relation thereto that by intermittently turning the trundle-wheel one-sixth of a rotation the angles and sides of the cam are alternately and successively brought to bear on the forward extension D⁷ and on the spring D⁹, secured to the rearward extension D⁸ of the pusher-bar D', having a bifurcated head (see Fig. 3) which reciprocates horizontally in suitable guideways within the attachment and is thus intermittently projected so that its bifurcations straddle the needle and against the edges of the fabrics, so as to push them from under the needle at each alternate descent of the needle-bar.

It is of great importance that the attachment, and particularly its pusher-bar, shall be capable of delicate adjustment relatively to the needle and to the edge of the goods and also of being firmly and positively secured in the desired position after such adjustment has been accomplished. In the operation of sewing, particularly in the case of heavy goods, very considerable transverse strain is brought to bear against the inclined work-face of the attachment C' as the goods are manipulated and fed forward, and it is therefore particularly desirable that the attachment shall be provided with bearings or connections relatively to the work-plate and base of the machine at at least two points, which shall not both be situated on the same

line extending either transversely to or parallel with the direction of the feed of the goods. I accomplish a preliminary and general adjustment and securement of the attachment relatively to the needle and to the edge of the goods by the means shown in the said previous patent, consisting of an extension B' of the base of the attachment B , containing a longitudinal recess B^2 , within which 10 slides a guide-block B^4 . A clamping-screw B^5 passes through the said guide-block and screwing into the base A of the machine clamps the attachment thereto. A screw-threaded rod B^6 extends from the guide-block B^4 and is threaded into the thumb-nut B^7 , the latter being provided with a collar B^8 , which turns in a recess B^9 . By these means, the clamping-screw B^5 being loosened, the rotation of the thumb-nut B^7 will move the attachment toward and away from the needle A^3 in a direction transverse to the direction of the feed, and when the requisite proximity to the needle or to the edge of the goods 15 has been obtained the attachment can be clamped firmly into place by tightening the screw B^5 . The leverage exerted by the fabrics and the manipulation thereof during sewing is, however, sufficient in many instances to change the desired angle of the work-face 20 C' relatively to the goods and also the position of the bifurcated pusher-bar, so as to cause it to be projected at an undesirable angle in relation to the needle and the presser-foot. To obviate these difficulties, I have 25 provided the attachment with my novel adjusting and fastening pin K , Fig. 8, having a cylindrical lower member or projection K' and an enlarged cylindrical portion or shoulder K^5 , disposed eccentrically in relation 30 thereto and provided, preferably, with an adjusting-handle K^2 , all rigidly secured together. I provide the work or sewing plate A with an elliptical or longitudinally-extending aperture K^8 , Fig. 7, in which fits loosely, 35 so far as movement transverse to the direction of the feed is concerned and closely so far as movement parallel with the line of feed is concerned, the lower member K' of the adjusting-pin. The cylindrical and eccentric 40 enlargement K^5 of the pin passes through and rotates within a closely-fitting perforation K^6 in the base B of the attachment, the handle K^2 projecting, as shown in Fig. 4, above the upper surface of the base. A set-screw K^4 45 is provided, passing through a perforation in the base and engaging with the shank of the pin, as shown in Fig. 5. The operation of the adjusting and securing pin K is as follows, the above-described parts having 50 been assembled as stated: After the requisite adjustment of the attachment toward the needle and the edge of the goods has been accomplished, as before described, by means of the thumb-screw B^7 and its correlated parts 55 the attachment may be adjusted with great delicacy and also with great ease transversely to the direction of the feed and so as to bring

the bifurcations of the pusher-bar into exactly the required relation to the needle by turning the pin K by means of the handle K^2 , 70 which will, as is obvious, move the attachment relatively to the center of rotation afforded by the clamping-screw B^5 . When the desired adjustment has been secured, the attachment can be fixed in position positively 75 and with great firmness by screwing up the set-screw K^4 and tightening the clamping-screw B^5 , and it will be observed that the combination, location, and operation of the adjusting and securing devices described are 80 such that they can be readily manipulated and operated by the fingers of one hand of the operator without relaxing the hold of the other hand upon the fabric as it is being manipulated and fed forward for the stitching 85 and that by the two bearings thus provided positive resistance will be afforded to movements of the attachment, and particularly of the bifurcations of the pusher-bar carried thereby relatively to the needle either transversely or parallel to the direction of the feed. 90

The feeder P of the machine operates in the usual way to move the goods forward. I have found that in the case of certain classes of fabrics—for instance, rough and heavy fabrics—a feeder having the usual roughened surface throughout its whole extent interferes with the successful manipulation of the edge of the fabric at and near the needle A^3 , (see Fig. 1,) the forward thrust of the pusher-bar in moving the edges of the fabric out of the way of the needle tending to unduly crowd them between the roughened surfaces of the feeder and the under side of the presser-foot in the immediate vicinity of the needle, whereby, owing to the roughened character of the feeder opposite the needle, is prevented the desired extent of return of the edge of the goods under and beyond the needle on the withdrawal of the pusher-bar. I obviate 100 these difficulties by cutting away the roughened portions of the surface of the feeder through part of its width directly opposite the needle and the pusher-bar and preferably also to some extent in advance of the 105 needle and also behind it. The portion of the surface of the feeder thus smoothed is preferably tapered away from directly opposite the needle in both directions and also preferably depressed somewhat below the bottom of the depression in the surface of the feeder, as shown at P' , Figs. 1 and 10, the feeder being thus provided with a depressed portion or recess P' , having the general shape described as above. By this means the desired uniform forward feed and return to normal position of the edges of the fabric is secured, notwithstanding the intermittent displacement thereof caused by the pusher-bar, and the natural resilience of the edges of the 125 fabric toward the needle after the withdrawal of the pusher-bar is relieved of impediment. It will be observed that this recess is preferably deeper at both ends thereof, its great- 130

est transverse dimensions, vertical and horizontal, being located opposite the needle. By thus shaping the recess the required control of and movement of the fabrics is more 5 perfectly secured.

Having thus described my invention, what I claim as new, and desire to secure by Letters Patent, is—

1. A sewing-machine attachment having a 10 base, a clamping-screw adapted to secure said base to the bed of the machine, a vertical circular perforation in said base, a cylindrical pin having an upper portion of enlarged horizontal cross-section eccentrically disposed 15 and fitting and rotatable in said perforation and a lower portion centrally disposed and fitting and rotatable in a perforation in the work-plate of the machine, means for locking said pin in the desired position, and a pusher- 20 bar reciprocating to move the edge of the fabrics from under the needle at each alternate descent thereof.

2. A sewing-machine attachment having a 25 base, a clamping-screw adapted to secure said base to the bed of the machine, a vertical circular perforation in said base, a cylindrical pin having an upper portion of enlarged horizontal cross-section eccentrically disposed 30 and fitting and rotatable in said perforation and a lower portion centrally disposed and fitting and rotatable in an elongated perforation in the work-plate of the machine, means for locking said pin in the desired position,

and a pusher-bar reciprocating to move the edge of the fabrics from under the needle at 35 each alternate descent thereof.

3. In a sewing-machine a presser-foot on one side of the needle, a pusher-bar on the opposite side of the needle reciprocating to move the edge of the fabrics under said presser-foot 40 and from under the needle at each alternate descent thereof, under said presser-foot, a roughened feeder provided with a recess having a smooth surface opposite, and in proximity, to the end of said pusher-bar, and 45 means for actuating said needle, pusher-bar, and feeder, substantially as and for the purposes described.

4. In a sewing-machine a presser-foot, on one side of the needle, a pusher-bar reciprocated from the opposite side of the needle to move the edge of the fabrics under said presser-foot and from under the needle at each alternate descent thereof, under said presser-foot, a roughened feeder having an unroughened recess tapered at each end, and having its greatest transverse horizontal and vertical dimensions opposite and in proximity to the end of said pusher-bar, and means for actuating said needle pusher-bar and feeder, substantially as and for the purposes described. 55 60
